CLAIM

The ornamental design of the combined modular children's activity and learning center, as shown and described.

DESCRIPTION

FIG. 1 is a top, front and left side perspective view of a combined modular children's activity and learning center showing my new design;

FIG. 2 is a front elevational view thereof;

FIG. 3 is a left side elevational view thereof;

FIG. 4 is a right side elevational view thereof;

FIG. 5 is a rear elevational view thereof; and,

FIG. 6 is a top plan view thereof.

The broken lines showing the letters "A", "B" and "C" as well as the words "cat" and "dog" are for illustrative purposes only and forms no part of the claimed design.
